UNITED STATES PATENT OFFICE.

ELIS OLSSON, OF WEST POINT, VIRGINIA.

METHOD OF CHARGING PULP DIGESTERS.

Application filed July 14, 1926. Serial No. 122,319.

This invention relates to pulp digesters. In order to convert wood chips or other material to be digested into pulp by the chemical process, the chips or other material are introduced into the digester and are treated with a suitable chemical solution which dissolves the binding material of the fiber. The chemical solution is usually introduced by gravity from tanks located 5 above the digester or is pumped thereinto from tanks located below the digester.

This invention has for its salient object to increase the capacity of a pulp digester.

Another object of the invention is to utilize a high pressure stream of chemical solvent liquor to pack the chips in the digester.

Another object of the invention is to so charge the digester with chips and solvent liquor that the chips will be packed by the stream of liquor.

Further objects of the invention will appear from the following specification taken in connection with the drawings, which form 25 a part of this application, and in which

Fig. 1 is an elevational view somewhat diagrammatic showing the arrangement of the apparatus constructed in accordance with the invention and adapted to carry out the 30 method of charging pulp digesters;

Fig. 2 is a top plan view of the structure shown in Fig. 1;

Fig. 3 is an enlarged detail view showing the hopper discharge spout for the chips and 35 the liquor conduit and nozzle; and

Fig. 4 is a view taken at right angles to Fig. 3.

In carrying out the method, chips are introduced into or deposited in the digester 40 simultaneously with the liquor and the force of the liquor stream is used to pack the chips. In the apparatus illustrated for carrying out the invention, the chips or other material are permitted to fall by gravity 45 from a hopper and the stream of liquor is pumped through a conduit and nozzle, means being provided for directing the stream in the desired direction to pack the chips. Further details of the invention will 50 appear from the following description.

In the form of the invention illustrated, a plurality of digesters A, B and C are positioned beneath discharge spouts 10, 11 and 12 of a chip bin or hopper 13. Means, such 55 as a valve 14, may be provided in each of the

spouts 10, 11 and 12 for regulating the flow of chips through the spout.

The solvent liquor is contained in a tank 20 and is pumped by a pump 21 into a main conduit 22 and from this main conduit into branch conduits 23. Each branch conduit may have a valve 24 therein for regulating the flow of liquor through the conduit and each conduit has a flexible conduit or hose 25 secured thereto and a nozzle 26 secured to the other end of each hose. A handle 27 is secured by clamps 28 to each of the hoses 25 and by means of the handle, the hose can be angled so as to direct the stream against different portions of the chips. The liquor is pumped through the nozzles 26 at relatively high pressure, such, for instance, as sixty pounds or over.

Care is taken in introducing the chips and the stream into the digester to so regulate the rate of charging the chips and stream that the chips will not float or be covered by the liquor but will be packed thereby.

The force of the stream directed from the nozzle against the chips, packs the chips and utilizes the full capacity of the digester.

By means of the method and apparatus above described, the yield per digester can be materially increased since more chips or other material to be converted into pulp can be digested in the apparatus than by the usual method. In this way, the cost of digesting the pulp can be materially reduced.

Although one particular form of apparatus has been illustrated for carrying out the invention, it will be understood that changes in the construction and in the arrangement of the various parts may be made without departing from the spirit or scope of the invention, as expressed in the following 95 claims.

What I claim is:

1. A method of charging pulp digesters which consists of introducing a stream of solvent liquor into the digester under high pressure, introducing the material to be digested into the digester simultaneously with the liquor and utilizing the force of the liquor stream to pack the material to be digested in the digester.

2. A method of charging pulp digesters which consists of introducing a stream of solvent liquor into the digester under pressure, introducing the material to be digested into the digester simultaneously with the

liquor and utilizing the force of the liquor stream to pack the material in the digester, the liquor and material being so introduced that the material will not be submerged in 5 or float on the liquor.

3. A method of charging pulp digesters which consists of introducing pulp material to be digested and a high pressure stream of

solvent liquor into a digester and directing the stream against the material to be digested to utilize the force of the stream to pack the material to be digested in the digester. 10

In witness whereof, I have hereunto set my hand this eighth day of July, 1926.

ELIS OLSSON.
